(57) **CLAIM**

The ornamental design of a transport case for portable expanding file folders, as shown and described.

DESCRIPTION

FIG. 1 provides a perspective view of the transport case for portable expanding file folders when in a closed position.

FIG. 2 provides a front cover elevational view of the transport case for portable expanding file folders.

FIG. 3 provides a rear cover elevational view of the transport case for portable expanding file folders.

FIG. 4 provides a top edge plan view of the transport case for portable expanding file folders in a closed position.

FIG. 5 provides a spine (bottom) edge plan view of the transport case for portable expanding file folders.

FIG. 6 provides a left side edge plan view of the transport case for portable expanding file folders in a closed position.

FIG. 7 provides a right side edge plan view of the transport case for portable expanding file folders in a closed position; and,

FIG. 8 provides a perspective view of the transport case for portable expanding file folders when in an open position. The broken lines define a file folder of the type which can be placed within the design and form no part of the claimed design.
